DAMPER CONTROLLER

John E. Haines, Gordon F. Laing, and Stanley W. Nickells, Chicago, Ill., assignors to Minneapolis-Honeywell Regulator Company, Minneapolis, Minn., a corporation of Delaware

Application October 11, 1939, Serial No. 298,924

8 Claims. (Cl. 236—16)

The present invention relates to damper load compensators which can be readily installed on furnaces. More specifically, our invention pertains to means to compensate for the weight of the dampers, to thereby obtain more sensitive operation thereof.

The draft and check dampers usually provided on a furnace are ordinarily formed of heavy cast metal. It is also a common practice to have the damper regulator operate the dampers by sequentially lifting said dampers off their respective seats. Because of the weight of the dampers, the damper motor will have a substantial reversal loss after one of the dampers is set down on its seat and before the second damper is lifted off its seat. In many installations this reversal loss amounts to 30 to 40 degrees F. of boiler water temperature, or 1½ to 2 pounds of steam pressure. Therefore, when a damper controller actuates heavy dampers there is no accurate control of the steam pressure or boiler water temperature.

Most furnace dampers are mounted upon a door, or upon a damper seat casting. They are often of different sizes and shapes suitable to the particular installation. Also, different manufacturers build different sizes, shapes, and weights of dampers, doors, and the accompanying fittings. These variations make it very difficult, or impossible, to actually counterbalance, or counterweight, each damper as it is installed upon the furnace.

It is an object of this invention to compensate the damper controller for the weight of the damper.

Another object is to provide damper weight compensating means which are adaptable to existing furnace installations.

A further object is to provide a compact device to accomplish the results of the preceding objects which will be very simple to install and adjust.

Other objects will be apparent in the specification, claims, and by reference to the accompanying drawing in which:

Figure 1 is a diagrammatic view of a form of our invention as applied to a hot water furnace.

Figure 2 is a diagrammatic view of another form showing different modifications.

Figures 3 and 4 are detail views of one form shown in Figure 2.

Figures 5 and 6 are diagrammatic views of modifications.

Figure 6a is a detail view of a part shown in Figure 6, and

Figure 7 is a diagrammatic view of another embodiment of the invention.

In Figure 1 a furnace 10 is conventionally provided with a draft port 11, draft damper 12, flue 13, and a check damper 14, which cooperate with a boiler temperature responsive damper motor 15 to control the flow of air through the furnace 10.

The damper motor 15 is provided with a base 17 which is screwed into the furnace 10 at 18. A volatile filled temperature bulb 19 extends into the furnace 10 and communicates with the diaphragms 20 within the motor 15. Therefore a rise in temperature at the bulb 19 will cause an increased pressure within the bulb and within the diaphragms 20 thus causing them to expand. The movement of the diaphragms 20 is transferred to a stem 21 which protrudes through a hole in the top of an upper part of the casing 16 and, by such movement, rocks a channel member 22 about a pivot 23 which is suitably secured by a bracket 24 to the upper part of the casing 16. The channel member 22 is provided with an arm 25 which extends to the left of the pivot point 23 and carries a weight 26 which may be moved to different positions along the arm 25 to vary the force acting downwardly upon the stem 21. Thus a manual adjustment is obtained to cause the motor 15 to actuate the dampers 12 and 14 at selectively different temperatures.

The channel member 22 is provided with a second pivot 28 upon which an arm 30 is rotatably mounted. The arm 30 is connected to the check damper 14 by a chain 31. A second arm 32 is rotatably mounted on the pivot 23 and is connected to the draft damper 12 by the chain 33. The arm 32 has an abutting end 34 which is adapted to engage the channel member 22 to thereby cause the draft damper 12 to open when the channel member 22 is being rotated counter-clockwise by the weight 26 due to a lowering of the boiler temperature. The arm 30 is provided with an abutting portion 35 which is adapted to engage the channel member 22 to cause the check damper 14 to open when the channel member 22 is being rotated clockwise by the motor 15 due to a rise of the boiler temperature. The arm 32 is provided with a screw stem 36 and the arm 30 is provided with a screw stem 37 which are connected by a spring 38. These screw stems form adjustable bell cranks in cooperation with the arms 30 and 32 as they are pivoted around their pivot points 28 and 23, respectively. The length of the arms thus formed by the screw stems 36 and 37 may be varied by changing the depth to

which they are screwed into their respective lever arms 32 and 30 and will change the effect of the spring 38 upon the lever arms 30 and 32. Therefore, an adjustment can be made for dampers which are of different weights or operate through different angles.

In operation the spring 38 is adapted to compensate the regulator for the weight of the dampers 12 and 14. In the position shown in Figure 1 the check damper 14 is closed and the draft damper 12 is open. Assuming now, for example, that the weight of the dampers 12 and 14 acting on the motor 15 is two pounds each and the force exerted on the arms 30 and 32 by the spring 38 through the bell crank arrangements is $1\frac{1}{4}$ pounds; then, even though the check damper 14 is in closed position there is still a $1\frac{1}{4}$ pound force tending to open said damper. Likewise when the draft damper 12 is in closed position and the check damper 14 is in open position the spring 38 will be exerting a similar $1\frac{1}{4}$ pound force tending to open the damper 12. It is seen that even when the dampers are in closed position, they are actually only engaging their damper seats by a force amounting to approximately $\frac{1}{4}$ of a pound. Therefore when the pressure motor 15 is moving to close one of the dampers and to subsequently open the second damper the additional weight that the damper motor needs to pick up is only $\frac{1}{4}$ of a pound rather than the entire weight of the damper. Thus the reversal loss which results when the motor is merely building up enough force to overcome the dead weight of the damper before that damper can be moved away from its seat is substantially reduced. So it is seen that by connecting the arms 30 and 32 by means of the screw stems 36 and 37 and the spring 38 that the weight of the dampers is in effect counterbalanced except for $\frac{1}{4}$ of a pound. This actual seating weight can be lower or higher if desired. It is also seen that by resiliently connecting the two dampers, the weight of one of the dampers, even though it is upon its seat, is still effectively counterbalancing the weight of the other damper to a certain extent because of the unique arrangement of the spring 38 and the abutting stops 34 and 35.

Referring now to Figure 2; the damper motor 15 is adapted to cooperate with an arm 39 which has a weight 40 adapted to oppose the movement of the stem 21 of the motor 15. The left hand end of the arm 39 is provided with a bracket 41 to which an arm 42 is rotatably mounted by a pivot 43. The arm 42 is provided with a weight 44 which may be adjustably positioned upon the arm 42. The weight 44 also serves as a stop in opening the damper (not shown) by abutting the arm 39. On the opposite end of the arm 42 a damper chain 45 can be connected.

By using a weight type of counterbalancing means, substantially the same result is obtained as in using the spring type of counterbalancing means hereinbefore described. Assuming, for example, that the damper connected to the chain 45 exerts a downward force of 2 pounds and the weight 44 weighs $1\frac{1}{4}$ pounds and both are effectively equidistant from the pivot 43; then, when the damper connected to the chain 45 is in closed position, the arm 39 is still supporting the weight of the weight 44 as well as the amount of weight of the damper connected to the chain 45 that is counterbalanced by said weight 44. In other words, the arm 39 supports $3\frac{1}{4}$ pounds

(weight of damper plus weight 44) when the damper is open and $3\frac{1}{2}$ pounds (counterbalanced weight of damper plus weight 44) when the damper is closed. Thus it is seen that when the damper connected to chain 45 is in closed position the weight 44 will act to, in effect, counterbalance for almost all of the weight of the damper.

Referring now to Figures 3 and 4; a detailed view is shown of that form of our invention mounted on the right hand end of the lever arm 39 and is generally indicated by the reference character 50. A short lever arm 51 extends through a slot (not shown) in a protective casing 52 and is connected to a chain 53 which in turn connects to a damper (not shown). The arm 51 is an extended portion of a circular plate 54 which is free to pivot about a stationary hub 55 suitably connected to the arm 39. The hub 55 is resiliently connected to notches 56 in the plate 54 by a spiral spring 57. The spring 57 is preferably one of open convolutions so that the parts of the spring will not rub against each other and cause spring friction in the operation of the device. The plate 54 is provided with an inturned ear 58 which is adapted to abut the arm 40 when that arm has been raised to a predetermined position to cause opening of the damper connected to the chain 53. The spring 57 is adapted to substantially counterbalance the weight of the damper connected to the chain 53. For example, the spring might exert a force of $1\frac{1}{4}$ pounds to the lever 51 when used with a damper that exerted a downward force of 2 pounds. Different springs may be easily inserted into the device for different weight dampers, and a different initial tension on the spring may be obtained by moving the free end of the spring into different notches 56 in the plate 54. Therefore this type of device, like the others hereinbefore described, is adapted to effectively counterbalance for the weight of the damper when the damper to which it is connected by the spring 53 is in engagement with its seat.

Referring now to Figure 5 the pressure motor 15 has a stem 21 adapted to actuate an arm 60. A weight 61 is mounted on the arm 60 to oppose the operation of the pressure motor 15. A damper weight compensating mechanism, generally indicated by the reference character 62, is mounted on a bracket on the left hand end of the arm 60. A bell crank 64 is pivotally mounted upon the bracket 63 by a pin 65. One arm of the bell crank 64 is connected to a damper chain 66. The other arm of the bell crank 64 is connected to a spring 67 which is in turn connected to a bracket 68 secured to the arm 60 in a conventional manner. A pair of stops 69 are provided on the bracket 63 and serve to limit the movement of the bell crank 64. The operation of this form of our invention is similar to the operation of those hereinbefore described. The effect of spring 67 is to continue to exert force upon the arm 60 even when the damper connected to the chain 66 is seated.

Mounted on the right hand end of the arm 60 is another form of compensating mechanism which embodies the use of a compression spring 71. This spring 71 is secured to the arm 60 by a U-shaped support 72 which is adapted to hold the spring 71 by its out-turned ends 73. The topmost convolution of the spring 71 is inturned and extended downwardly through the interior of the spring, and the end is looped to form a connection 74 to which a damper chain 75 can be

attached. The function of this form of weight compensator is substantially the same as the forms hereinbefore described in that it acts to exert a force upon the damper motor arm even when the damper is in the closed position.

Referring now to Figure 6; the damper motor 15 has the operating stem 21 in cooperative relation with an arm 80. The arm 80 is provided with a weight 81 which is adapted to oppose the movement of the motor 15. The extremities of the arm 80 are provided with compensating means generally indicated by the reference characters 82 and 83. The parts used in each of the compensators are identical and are merely arranged differently so as to show their application on 15 damper motors where the clearance above or below the extremities of the damper arms are different, therefore only one of them will be explained in detail. The compensator 83 comprises a leaf spring 84 suitably secured to the arm 80 by a clip 85. The leaf spring 84 is provided with a down-turned end 86 which is adapted to be inserted into holes on the top of the arm 80 as is indicated at 87. The opposite end of the leaf spring 84 is arcuately formed as indicated at 88. A link 89 is adapted to fit loosely over the arm 80 which extends through a slot 91 in the link 89. Holes 92 are provided whereby the damper chain 93 may be hooked to the link 89 at different heights. The link may be used with the slot 91 in an upward position as is shown in the compensator-arrangement generally indicated at 83 or it can be used with the slot 91 in a downward position as used in the compensator-arrangement indicated at 82. The effect of this compensator in operation is substantially the same as that in the other forms hereinbefore described in that it tends to exert a force upon the damper arm 80 even when the damper is in the closed position.

Referring now to Figure 7; the damper motor 15 cooperates with a damper arm 100 which is provided with a weight 101 that is adapted to oppose the movement of the stem 21 of the motor. A damper chain 102 connects the damper arm 101 with a damper load compensator generally indicated by the reference character 103. The compensator 103 is adapted to be mounted upon the damper and is shown as mounted to a lug 104 upon a damper 105 by a screw 106. The compensator 103 comprises a coil spring 107 secured to a fixed support 108 at one end. A free end 109 of the spring 107 is turned to form a loop to which the damper chain 102 is secured. A stop 110 is provided to limit the movement of the free end 109 of the spring 107. The operation of this form of our invention is substantially the same as the function of those forms hereinbefore described in that the spring 107 tends to exert a force upon the damper motor arm 100 even when the damper 105 is seated.

While we have shown some modifications of our invention in applications where different forms have been used on different extremities of the damper motor arm, it will be understood that the same type of compensator could be used on either end, or that different types might be used on either end as shown. It will also be obvious that for different sizes and weights of dampers different modifications might prove to be the best applicable. Therefore it should be clearly understood that we are not to be limited in our invention only to those forms and combinations shown and described but by the spirit and scope of the appended claims.

We claim as our invention:

1. A damper mechanism comprising, in combination, a damper movable into and out of engagement with a damper port, a damper motor for moving said damper, said damper exerting a force upon said motor when away from said port, a damper arm operated by said motor, a coiled spring carried by said arm, a lever also carried by said arm adjustably secured to said spring, said spring exerting a force at all times tending to move said damper out of engagement with said port to compensate said motor for the weight of said damper, and connecting means between said damper, said motor, and said spring.

2. A damper mechanism comprising, in combination, a damper movable into and out of engagement with a damper port, a damper motor for moving said damper, said damper exerting a force upon said motor when away from said port, a damper arm operated by said motor, a coiled spring carried by said arm, a lever also carried by said arm adjustably secured to said spring, said spring exerting a force at all times tending to move said damper out of engagement with said port, connecting means between said damper, said motor, and said spring, and a stop carried by said lever engageable with said arm upon movement thereof in a damper opening direction to form a non-yieldable connection between said motor and said damper for moving said damper away from said port.

3. A damper mechanism comprising, in combination, a damper movable into and out of engagement with a damper port, a damper motor for moving said damper, said damper exerting a force upon said motor when away from said port; a damper arm operated by said motor, connecting means between said motor and said damper, a biasing means located in said connection between said motor and said damper, said biasing means exerting a force at all times tending to move said damper out of engagement with said port, and a stop means forming a non-yieldable connection between said motor and said damper for moving said damper away from said port.

4. A damper mechanism comprising, in combination, a damper movable into and out of engagement with a damper port, a damper motor for moving said damper, said damper exerting a force upon said motor when away from said port, a damper arm operated by said motor, a biasing means supported entirely by said arm, said biasing means exerting a force at all times tending to move said damper out of engagement with said port, connecting means between said damper, said motor, and said biasing means, and a stop means forming a non-yieldable connection between said motor and said damper for moving said damper away from said port.

5. In a heating system, in combination, fuel burning means including a draft damper and a check damper, a chamber associated with said fuel burning means and adapted to expand on increased rates of heat production within said fuel burning means, pivoted lever means adapted to be positioned by expansion and contraction of said chamber, connections between said lever means and said dampers for opening said draft damper when heat is being produced at a relatively low rate and for opening said check damper when heat is being produced at a relatively high rate, biasing means interposed in one of said connections acting in a direction tending to cause 70 opening of the damper to which said connection 75

is attached, and stop means for rendering said biasing means ineffective at values of force above a predetermined magnitude transmitted by said lever to said connection, whereby the force transmitted to said lever means by said chamber necessary to open said damper means is only slightly greater than the force necessary to load said resilient means to the point where said stop means is effective.

6. In a heating system, in combination, fuel burning means including a draft damper and a check damper, a chamber associated with said fuel burning means and adapted to expand on increased rates of heat production within said fuel burning means, pivoted lever means adapted to be positioned by expansion and contraction of said chamber, connections between said lever means and said dampers for opening said draft damper when heat is being produced at a relatively low rate and for opening said check damper when heat is being produced at a relatively high rate, resilient biasing means interposed in one of said connections acting in a direction tending to cause opening of the damper to which said connection is attached, and stop means for rendering said resilient biasing means ineffective at values of force above a predetermined magnitude transmitted by said lever to said connection, whereby the force transmitted to said lever means by said chamber necessary to open said damper means is only slightly greater than the force necessary to load said resilient means to the point where said stop means is effective.

7. A damper mechanism comprising, in combination, first and second dampers movable into and out of engagement with corresponding ports, a fluid pressure actuated damper motor for moving said dampers out of engagement with their

ports selectively, the first of said dampers exerting a force upon said motor when away from its port, an arm operated by said motor, first connecting means between said arm and said first damper, said first connecting means having a variable effective length, biasing means associated with said first connecting means and tending to vary the effective length thereof in a direction tending to open said first damper, stop means for limiting the effective length of said first connecting means so that said motor may positively open said first damper, and second connecting means between said arm and said second damper, said second connecting means being separate from said first connecting means.

8. A damper mechanism comprising, in combination, first and second dampers movable into and out of engagement with corresponding ports, a fluid pressure actuated damper motor for moving said dampers out of engagement with their ports selectively, the first of said dampers exerting a force upon said motor when away from its port, an arm operated by said motor, first connecting means between said arm and said first damper, said first connecting means having a variable effective length, a spring means associated with said first connecting means and tending to vary the effective length thereof in a direction tending to open said first damper, stop means for limiting the effective length of said first connecting means so that said motor may positively open said first damper, and second connecting means between said arm and said second damper, said second connecting means being separate from said first connecting means.
